UNITED STATES PATENT OFFICE.

LOUIS CLARKE, OF COLLEGE POINT, NEW YORK.

BOTTLE-CLEANER.

1,276,874.

Specification of Letters Patent. Patented Aug. 27, 1918.

Application filed June 10, 1918. Serial No. 239,297.

To all whom it may concern:

Be it known that I, LOUIS CLARKE, a citizen of the United States, residing at College Point, in the county of Queens, State of New York, have invented certain new and useful Improvements in Bottle-Cleaners; and I do hereby declare the following to be a full, clear, and exact description of the invention, such as will enable others skilled in the art to which it appertains to make and use the same.

The present invention relates to new and useful improvements in rotary cleaning devices, adapted for cleansing the interiors of bottles or like receptacles, and more particularly of that type including a screw threaded shank and a member mounted on the shank for relative longitudinal non-rotative movement whereby upon the occurrence of said movement, the shank will be rotated to effect a cleansing action through the medium of brush members carried thereby.

It is in general the object of the present invention to simplify and otherwise improve the structure of devices of this character, and to increase the efficiency of such devices and the ease with which they may be manipulated.

More particularly it is my object to provide a device wherein the threads of the shank are formed by the twisted relation of wire strands composing the shank and whereby said strands are separated and extended at the end of the shank to form brush carrying members, thus providing for manufacture of the device at an exceedingly low cost.

With the above and other objects and advantages in view, the invention resides more particularly in the novel combination, formation and arrangement of parts herein-after described and particularly pointed out in the appended claims.

Figure 1 is a perspective view of the improved rotary cleaning device.

Fig. 2 is an elevational view thereof, with portions in vertical section.

Fig. 3 is an elevational view showing the device ready for insertion in a bottle.

Fig. 4 is a transverse sectional view on the line 4—4 of Fig. 2.

Referring now more particularly to the accompanying drawings, the main shank of the cleaning device is formed of a plurality of, in the present instance three, wire strands

5, which are twisted about one another to form spiral thread grooves in the shank. At the upper end of the shank, the wires are preferably pressed together to form a substantially cylindrical head portion on which is 60 rotatably mounted a handle cap 6 and which is provided with an annular groove 7 receiving an inward projection 8 on said cap affording a swivel securement for the cap. At the other end of the shank, the wire strands 5 are separated and extend a considerable distance from the shank, being resilient in nature and normally urged apart. A pair of these shanks carry brushes 9, and the remaining strand carries a chain 70 section 10 adapted to clean the bottom of a bottle when it is placed therein. For rotating the shank upon reciprocation thereof, and for also procuring a retraction of the brush and chain carrying strand portions to 75 permit their ready insertion in a bottle or other receptacle to be cleaned, a plate 11 is mounted on the shank, and provided with an opening 12 corresponding in area to the cross sectional area of the twisted strands, 80 portions of the plate thus extending into the thread grooves of the shank whereby when the plate is held against rotation, a rotative movement will be imparted to the shank upon reciprocation thereof with respect to the plate. A second plate 13 is also provided which is movable about the separate strand portions to draw them together and permit the ready insertion of said strand sections in a bottle. 90

Thus, in operation the plate 13 is normally positioned to retract the separate strand portions, and the brush and chain members carried thereby are inserted into the neck of a bottle or other receptacle. The 95 device is then pushed into the receptacle, the plate 13 abutting the mouth of the receptacle and as the separate strand sections move inwardly they are freed from the plate and assume their normal positions to engage their work members with the wall of the receptacle. With one hand the operator then presses the plates 11 and 13 against the receptacle, and with his other grasping the handle cap 6 reciprocates the shank to 100 thus move the brushes and chain members up and down in the bottle and at the same time effect rotation thereof, or the plate 11 itself may be reciprocated to confine the cleaning action to one portion of the bottle. 110

A simple, durable and efficient device has thus been provided, which may be manufactured at an exceedingly low cost.

What is claimed is:

- 5 1. A rotary cleaning device including a shank comprising a plurality of strands twisted together to form spiral thread grooves, a handle swiveled at one end of the shank, said strands being separated and extending divergently at the other end of the shank, cleaning members carried by said separated strand portions, and a member 10 slideable on the shank and having portions engaged in the thread grooves thereof.
- 10 15 2. A rotary cleaning device including a shank comprising a plurality of strands twisted together to form spiral thread

grooves, a handle swiveled at one end of the shank, said strands being separated and extending divergently at the other end of the shank, cleaning members carried by said separated strand portions, and a member 20 slideable on the shank and having portions engaged in the thread grooves thereof and a second member slideable on the shank and 25 extensible over the separated strand portions to retract said portions.

In testimony whereof, I affix my signature, in the presence of two witnesses.

LOUIS CLARKE.
